UNITED STATES PATENT OFFICE.

CLIVE SELSEY PHILLIPS, OF LONDON, ENGLAND, ASSIGNOR OF ONE-HALF TO FRED-
ERICK RICHARD SIMMS, OF LONDON, ENGLAND.

TAP FOR FLUIDS.

Application filed February 5, 1927, Serial No. 166,033, and in Great Britain November 11, 1925.

This invention relates to improvements in taps for fluids, more particularly designed for use with oil drums and barrels, of the kind comprising two telescoping tubular members, which are formed with slots or apertures so arranged that when the members are collapsed the tap is closed and in an extended position of the said members the slots or apertures provide a free passage for the flow of the fluid from the container.

According to my invention in a tap of the described type I so construct the said members that when they are extended and relatively rotated the slots or apertures therein provide a free passage for the flow of the fluid from the container.

In a suitable arrangement embodying the invention the tap comprises two telescoping tubular members the inner of which is closed at the ends and provided with a slot or aperture near each end and the other or outer member provided near the front end with a similar slot or aperture with which the rear slot in the inner member is designed to register when the said member is extended and partially rotated by a projecting knob or enlargement at its outer end. Means, such as a longitudinal slot in the outer member with which engages a pin in the inner member, are provided for preventing the inner member from being rotated until it is fully extended, and also for the retention of the tap in the fully open position, such latter means consisting, for example, of a niche or right-angled extension of the front end of the longitudinal slot into which the aforesaid pin fits and is moved to bring the apertures into coincidence. The rear end of the longitudinal slot may be formed with a rearwardly inclined extension so that in the closed position the inner tubular member can be rotated to make a fluid-tight joint between the knob on its outer end and the front end of the outer member, in the known manner.

The operating knob on the inner telescoping member may, however, be dispensed with and a key employed instead and for this purpose the closure at the front end of the said member is formed hollow to receive the bit of the key with a key-hole in the front wall so that the bit when inserted can be turned to engage between the said wall and the rear wall and effect the longitudinal movement of the member, the bit making

contact with a stop in either direction of rotation to effect the required rotation of the said member.

To enable the invention to be fully understood I will describe it by reference to the accompanying drawing, in which:

Figures 1, 2 and 3 are, respectively, a side view, a front view and underside view of a tap for fluid, constructed in accordance with the invention.

Figure 4 is a section on the line 4—4, Figure 1.

Figure 5 is a section on the line 5—5, Figure 3.

Figures 6 and 7 are views similar to Figures 1 and 5, respectively, showing different positions of the parts of the tap.

Figure 8 is a section on the line 8—8, Figure 7.

Figure 9 is a view similar to Figure 2, showing the tap designed to be operated by a key.

Figure 10 is a section on the line 10—10, Figure 9.

Figure 11 is a section on the line 11—11, Figure 10.

Figures 12 and 13 are, respectively, a side view and an end view of the key to be used with the tap shown in Figures 9 to 11.

Referring to Figures 1 to 8, *a* and *b* are, respectively, the inner and outer telescoping tubular members of my improved tap, *c*, *d* being the closures at the inner and outer end of the said inner member, respectively. *e*, *f* are the slots or apertures in the wall of the rear and front ends, respectively, of the inner member *a*, whilst *g* is the slot or aperture in the wall at the front end of the outer member *b*, with which aperture the rear aperture *e* of the member *a* is designed to register as shown in Figure 7, when the latter member is moved by means of the knob or enlargement *a'* on its front end, from the position indicated in Figure 1 to that indicated by the dot and dash lines in Figure 6, and partially rotated. *h* is the longitudinal slot in the outer member *b* and *i* is the pin on the member *a* which engages with the said slot. *j* is the niche or right-angled extension of the front end of the longitudinal slot *h* into which the pin *i* is turned in the fully extended position of the inner member *a* to bring the aperture *e* into complete coincidence with the aperture *g*. *j'* is the extension of the rear end of the longitudinal slot *h* into which the pin *i* is turned in the closed position of the inner member *a* to effect a fluid-tight joint between the knob on its outer end and the front end of the outer member *b*.

h which is rearwardly inclined, so that by rotating the inner member *a* to engage the pin *i* with the said slot when the said member is in the closed position, a fluid-tight joint will be made between the knob *a*¹ and the front end *b*¹ of the outer member *b*. A suitable gasket, such as is shown at *h* may be employed. The said end *b*¹ is provided with a suitable packing ring *k*¹, and is shown as being of polygonal form in order that the outer member *b* can be screwed by a spanner into the necessary opening in the container vessel *A*, which is indicated by dot and dash lines in Figures 1, 5 and 7, the said member and opening being formed with corresponding screw-threads for this purpose, as indicated.

The tap is operated as follows:—

In the normal, or closed position, the two tubes *a* and *b* are collapsed to the position shown in Figures 1, 3 and 5 and the knob *a*¹, on the outer end of the inner member *a*, is all that projects beyond the wall of the container *A*. If it be desired to withdraw the fluid from the container *A*, the inner member *a* is twisted anti-clockwise by the knob *a*¹ and then pulled outwards as far as possible to the position indicated in Figure 6. It is then turned through an angle of 180° to bring the apertures *e* and *g* in the inner and outer members, respectively, into register, as indicated in Figures 7 and 8, thus providing a free passage through the said inner member *a* for the fluid which issues through the aperture *f* in the front end of the said inner member.

Figures 9 to 18 show the arrangement where the knob *a*¹ is dispensed with and the inner member *a* constructed so as to require a key for its manipulation. In this arrangement the closure *d* is made hollow to form the space or chamber *l* to receive the bit *m* of the key, Figures 12 and 13, which is inserted through the key-hole *n* in the front wall *o* of the chamber *l* and turned to fit between the said wall and the rear wall *p*. This engagement of the key-bit between the two walls *o* and *p* enables the longitudinal movement of the inner member *a* to be effected by the key. *q*, *q* are the stops within the chamber *l* with both of which the key-bit *m* is turned into contact in either direction to rotate the member *a* so as either to engage the pin *i* with the slot extension *j* or the slot extension *j*¹.

Although the invention is described more particularly for use with oil drums or barrels, it is to be understood that it is also applicable to any type of container for liquids and to terminal taps on pipes for water and other fluids, especially where economy of space is an object.

Claims:

1. A tap for fluids comprising two telescopically fitted and relatively rotatable

tubular members, one of said members having a discharge aperture, said members each having an inlet aperture, means for guiding the relative movement of said members, said guiding means permitting a limited relative rotative movement when the members are in extended position to bring the inlet apertures into register, and means for causing relative rotative movement between the members.

2. A tap for fluids comprising two telescopically fitted and relatively rotatable tubular members, one of said members having a discharge aperture and each of said members having an inlet aperture, one of said members provided with a slot, a pin carried by the other of said members and arranged to operate in said slot, said slot constructed to permit limited relative rotative movement of said members when in extended position to bring the inlet apertures into register, and means to cause relatively rotative movement between the members.

3. A tap for fluids comprising two telescopically fitted and relatively rotatable tubular members, the inner member being provided with inlet and discharge apertures and the outer member being provided with an inlet aperture, one of said members being provided with a guiding slot, a pin on the other of said members to engage and operate in said slot, said slot constructed to permit limited rotative movement of 180 degrees between said members when the inner member is in extended position and to prevent relative rotation between said members during the movement of the inner member from extended to telescoped position, and means to produce relative rotative and telescopic movement of said members.

4. A tap for fluids comprising two telescopically fitted and relatively rotatable tubular members, the inner member being provided with inlet and discharge apertures, and the outer member being provided with an inlet aperture adapted to register with the inlet aperture of the inner member, a substantially Z shaped slot in the outer member, a pin carried by the inner member and engaged with and operating in said slot, said slot having a portion to permit relative rotative movement of said members through 180 degrees to bring the inlet apertures of said members into register and means to rotate the inner member.

5. A tap for fluids comprising two telescopically fitted and relatively rotatable tubular members, the inner member being provided with inlet and discharge apertures, and the outer member being provided with an inlet aperture adapted to register with the inlet aperture of the outer member when said inlet member is extended, said outer member having a longitudinal slot therein

- and a transverse slot at each end of the longitudinal slot and connected therewith, a pin on the inner member engaged in said slot and guided in its movement by the walls of 5 said slot, the forward transverse slot serving to permit limited relative rotative movement between said members through 180 degrees to bring the inlet apertures of said members into register, means to rotate the 10 inner member operable when in extended or telescoped position, and means acting to produce simultaneous longitudinal movement of the inner member when said member is rotated in substantially collapsed position.
- 15 6. A tap for fluids comprising two telescopically fitted and relatively rotatable tubular members, the inner member having its ends closed and being provided with inlet and discharge apertures and the outer member being provided with an inlet aperture, 20 one of said members being provided with a guiding slot, a pin on the other of said members to engage and operate in said slot, said slot constructed to permit limited relative rotative movement of 180 degrees between said members when the inner member 25 is in extended position and to prevent relative rotation between said members during the movement of the inner member from extended to telescoped position and means to produce relative rotative and telescopic 30 movements of said members.
- 25

CLIVE SELSEY PHILLIPS.
